DESIGN FOR A SHOE OR SIMILAR ARTICLE

Joseph Lanz, Salzburg, Austria

Application July 8, 1935, Serial No. 57,561

Term of patent 3½ years

To all whom it may concern:

Be it known that I, Joseph Lanz, a citizen of Austria, residing in Salzburg, Austria, have invented a new, original, and ornamental Design for a Shoe or Similar Article, of which the following is a specification, reference being had to the accompanying drawing, forming part thereof.

I claim:

The ornamental design for a shoe or similar article as shown.

JOSEPH LANZ.
